UNITED STATES PATENT OFFICE.

THOMAS C. FRESHOUR AND BERT M. JENNINGS, OF TROY, OHIO.

GARMENT-FORM SUPPORTER.

Application filed December 8, 1921. Serial No. 520,929.

To all whom it may concern:

Be it known that we, THOMAS C. FRESHOUR and BERT M. JENNINGS, citizens of the United States, residing at Troy, in the county of Miami and State of Ohio, have invented certain new and useful Improvements in Garment-Form Supporters, of which the following is a specification, reference being had therein to the accompanying drawing.

This invention relates to improvements in garment-form supporters.

The essential object of our invention is to provide such a supporter with an expandible shoulder rest and an expandible hip rest, whereby various sizes of these garment-forms may be readily and quickly positioned and held for use in fitting the garments to the forms.

Our invention also includes provision not only for lateral adjustment of such shoulder rests and hip rests but for relative vertical adjustment of these members so as to accommodate garment forms of varying lengths as well as varying lateral dimensions.

In the accompanying drawings,

Fig. 1 is a side elevation of our garment-form supporter in its entirety;

Fig. 2 is a view of such a garment form as will be applied to our supporter;

Fig. 3 is a plan view of the shoulder rest features; and

Fig. 4 is a plan view of the hip rest features.

Such a garment form as is illustrated in Fig. 2 is in common use among dress makers and garment fitters. These forms come in various sizes and various forms of outline. The object in view is to provide a supporter for the various sizes and shapes of these garment forms. To this end our supporter consists of a hollow or tubular base post 1 having a fixed collar 2 to which are attached several legs 3 by pivot bolts 4. This collar is at a suitable point above the lower end of the post and on the post below the collar is fitted a slidable sleeve 5 held in adjusted positions by a set screw 6 and having pivoted to it a brace 7 for each leg 3. Pivot bolts 8 connect the braces with the sleeve 5 and pivots 9 connect them with the legs 3. By sliding the sleeve to different positions the legs will be spread outward or drawn inward to accommodate them to the available floor space where the supporter is set up.

The post carries a fixed band or ferrule 10

provided with a set screw 11 whose office is to hold in adjusted positions the adjustable post 12 which is preferably tubular and which is telescopically fitted to the base post 1. In this way the height of the supporter may be determined at pleasure and the general position of the shoulder rest and hip rest may be made to suit.

The upper end of the slidable post carries the shoulder rest which consists of a fixed collar 13 having a curved transverse plate 14, an adjustable sleeve 15 having links 16 and shoulder pieces 17. The sleeve 15 is held in adjusted positions by a set screw 18 while the links 16 are pivoted to this sleeve at 19 and to the shoulder pieces at 20. Any adjustment up or down of the sleeve 18 will position the shoulder rest further outward or inward according to the adjustment. These rests slide on the bar 14 and are connected to it through guide pins 21 which are fixed in the plate 14 and extend through slots 22 in the rest 17, as better seen in Fig. 3. These rests have collar pieces 23 which are adapted to extend within the collar opening of the garment form.

It will now be understood that this shoulder rest is capable of vertical adjustment and lateral expansion and contraction so that it will support a garment form at any desired height as well as forms of various dimensions.

The hip rest comprises a slidable sleeve 24 held by a set screw 25 and carrying radial arms 26. These arms are slotted at 27 and carry each a guide bolt or pin 28. Fitted against the arms 26 are extension slides 29 which are slotted at 30 so as to slide on the bolts or pins 28 and which carry similar bolts or pins 31 which slide within the slots 27. In this manner the extension slides are duly supported in any of their laterally adjusted positions. Each slide has a lug 32 to which is attached a hip rest proper 33, as by means of rivets 34. These hip rests proper are curved to accommodate them to the curved line of the hip portion of the garment form.

To adjust the slides 29 and to further sustain them we provide braces 35 pivoted at 36 to the slides and at 37 to an adjustable sleeve 38 held by a set screw 39. When the hip rests are to be expanded the sleeve 38 is moved upward or the sleeve 24 is moved downward. When they are to be contracted the sleeve 38 is moved downward or the sleeve 24 upward. When the elevation of

the hip rest is to be changed both of the sleeves 24 and 38 are moved on the post 12, upward or downward, according to the distance desired between the hip rest and the 5 shoulder rest.

It will now be seen that with our garment-form supporter we provide for all of the possible adjustments that may be needed to accommodate it to the various sizes of garment forms, both as regards lengthwise and lateral dimensions. And also that the form is firmly held and conveniently positioned and made fully accessible when applied to our supporter.

Having thus fully described our invention, what we claim as new and desire to secure by Letters Patent, is:—

1. In a garment form supporter, the combination with a post having a suitable base; 20 of a shoulder rest mounted on the post and including a fixed collar, a lateral plate formed integrally with the collar and extending in opposite directions therefrom at each end, shoulder pieces slidably mounted 25 on the plate at each end thereof and having pin and slot connection therewith, a slidable sleeve mounted on said post, links each having one end connected to the slid- 30 able sleeve and the other end connected to a respective shoulder piece; and a hip rest comprising a pair of sleeves slidable on said post and movable independently of each other, radial arms projecting from one of 35 said sleeves, slides each having pin and slot connection with a respective arm, braces each having one end pivoted to a respective slide and the other end pivoted to the remaining sleeve of said pair, hip rests mounted 40 on the outer ends of said slides, and means to hold the several sleeves in adjusted positions.

2. In a garment form supporter, the combination with a post having a suitable base; 45 of a shoulder rest mounted on the post and including a fixed collar, a lateral plate formed integrally with the collar and extending in opposite directions therefrom at each end, shoulder pieces slidably mounted 50 on the plate at each end thereof and having pin and slot connection therewith, a slid- able sleeve mounted on said post, links

each having one end connected to the slid- able sleeve and the other end connected to a respective shoulder piece; and a hip rest comprising a pair of sleeves slidable on said post and movable independently of each other, radial arms projecting from one of 55 said sleeves, slides each having pin and slot connection with a respective arm, braces each having one end pivoted to a respective slide and the other end pivoted to the remaining sleeve of said pair, hip rests mounted 60 on the outer ends of said slides, and means to hold the several sleeves in adjusted positions; and a hollow post receiving the 65 lower end of the first mentioned post, means to adjust the first mentioned post within the hollow post, a fixed sleeve on said hollow post, a slidable sleeve on said hollow post, legs pivoted to the fixed sleeve, and links 70 each having one end pivoted to a respective leg and the other leg pivoted to the slid- able sleeve.

3. In a garment form supporter, the combination with a post having a suitable base; 75 of a shoulder rest mounted on the post and including a fixed collar, a lateral plate formed integrally with the collar and extending in opposite directions therefrom at each end, shoulder pieces slidably mounted 80 on the plate at each end thereof and having pin and slot connection therewith, a slidable sleeve mounted on said post, links each having one end connected to the slid- 85 able sleeve, the other end connected to a respective shoulder piece; and a hip rest comprising a pair of sleeves slidable on said post and movable independently of each other, radial arms having their inner ends pivoted to one of said sleeves, slides each 90 having pin and slot connection with a re- spective arm, braces each having one end pivoted to a respective slide and the other end pivoted to the remaining sleeve of said 95 pair, hip rests mounted on the outer ends of said slides, and means to hold the sev- eral sleeves in adjusted positions.

In testimony whereof, we affix our signatures.

THOMAS C. FRESHOUR.
BERT M. JENNINGS.
